COIN-CONTROLLED TIMING DEVICE FOR ELECTRICALLY-ACTUATED REFRIGERATORS
AND LIKE MACHINES

Application filed December 19, 1928. Serial No. 326,916.

This invention relates to improvements in coin-controlled timing devices for electrically-actuated refrigerators and like machines.

One of the objects of this invention is to provide a coin-controlled timing device by which electrically-actuated refrigerators, radio apparatus and like machines may be operated during a predetermined period of time for a coin of given denomination.

Still another object of my invention is to provide in a coin-controlled electrically-actuated device a timing element which will, without the use of springs or other intricate timing mechanism, at a predetermined period of time, actuate a switch preferably for the purpose of opening an electric circuit and thus cutting off current to such machine at the end of a predetermined period after the insertion of the coin and the starting thereby of the operation of the machine.

Still another object of my invention is to provide, in a device of the character described, an element operable upon the insertion of a coin by a simple rotary movement of the handle.

With these and other objects in view, the invention comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:

Fig. 1 is a longitudinal section of an apparatus embodying my invention being taken on the line 1—1 of Fig. 2;

Fig. 2 is a section on the line 2—2 of Fig. 1, looking in the direction of the arrow;

Fig. 3 is a side elevation of the timing device shown in Figs. 1 and 2;

Fig. 4 is a section on the line 4—4 of Fig. 2, looking in the direction of the arrow;

Fig. 5 is a section on the line 5—5 of Fig. 2, looking in the direction of the arrow; and

Fig. 6 is a section on the line 6—6 of Fig. 1, looking in the direction of the arrow.

Referring now to these drawings, which

illustrate a preferred embodiment of my invention, 1 indicates a suitable support which may be a part of a box or the like within which the apparatus is mounted so as to be completely enclosed and inaccessible except for exposure of the coin slot 2 and the operating handle 3.

In the preferred embodiment shown, an electric circuit E is closed by the depositing through the slot 2 of a coin and my device is arranged to break or open said circuit at the end of a predetermined period of time after the closing of the circuit. As illustrated, a coin C when passed through the coin slot 2 will be held in the position shown in dotted lines in the throat of the coin chute 4 and the coin C being releasable so as to drop into circuit-making position as shown in full lines at the bottom of Fig. 1, the coin C in this case forming the contact or bridging element between the circuit contact points or terminals 5 and 6 respectively, the opposite legs 7 and 8 of the circuit E being, as shown, connected to insulated portions 9 and 10 of the coin-chute 4. As illustrated, these portions 9 and 10 are insulated by a suitable piece of insulation 11 which completely insulates the two portions 9 and 10 from each other and enables these portions to act as terminals for the opposite legs 7 and 8 of a suitable electric circuit. As illustrated, I have mounted on one of said portions and preferably in the portion 10 a coin-stop 12 having a projecting portion 12' extending through a slot 12a in the said portion 10.

When a coin so deposited assumes the position at the lower end of the coin chute, as illustrated in full lines, the electric circuit E will be closed across the terminals 7 and 8.

This coin-stop 12, as illustrated, is resiliently moved into coin-engaging position by a flat spring 13 mounted on the casing 4 and, as shown, abutting against a piece of insulation 13' on the coin-stop 12. The coin-stop 12 is movable into and out of the path of the coin to release the same and permit it to fall by gravity into a suitable receptacle not shown.

The switch S in the circuit E is normally retained in closed position by the contact

member 14 which is insulated from and disposed at the end of one arm 15' of a lever 15 pivoted at 16, the contact member 14 being normally moved into contact-making position by a weight 17 adjustably mounted on the said arm 15.

Obviously if the contact member 14 is moved out of contact-making position, the switch S will be opened and the circuit will be broken so that no more current will flow through the legs 7', 8' of the electric circuit E to operate the motor for the refrigerator, or to supply current for a radio or other device which it is desired to operate. As illustrated, the making of the electric circuit E is arranged to start a motor M for operation of a refrigerating machine. Current is supplied from any suitable source of supply not shown, and when it is necessary to operate radio apparatus or other similar device, the motor M may be omitted.

It is often desirable to permit operation of an electric refrigerator, radio apparatus or like machine for a predetermined period 25 of time only and in order to accomplish this end, in the preferred embodiment illustrated, it is necessary to break the circuit by the opening of the switch S. I have, therefore, utilized a timing element for this purpose 30 which is extremely simple and accurate and eliminates the manifold springs and cog wheels usually incident to clock mechanisms.

I provide a sand-actuated time-measuring element T having oppositely-disposed compartments 18, 18' communicating through a sand-drip aperture 20. The fineness of said aperture 20 and the sand capacity of the device will determine the time necessary for the sand to pass through the aperture 20 40 from one compartment into the other. As shown, sand in the compartment 18 passes into the compartment 18' and the weight of a full load of sand in the compartment 18' will depress the lever 15^a against the action of the weight 17. This depression of the lever 15^a 45 will move the contact element 14 out of contact-making relationship with the switch S, which, of course, breaks the circuit E and stops the flow of current.

Now in order to enable the making and breaking of this circuit between the switch contact members s, s' to be quick-acting, I provide the element 14 with a notch 14' and also provide the switch S with a bent contact element s' which fits into said notch. It will be obvious that when a predetermined weight of sand is applied on the lever 15^a the weight 17 will be overbalanced and the member 14 will be disengaged from the switch S, 60 and this disengagement will, in view of the notch 14' and bent contact element s', be caused to act quickly and thus avoid arcing.

In the position of the parts shown in Fig. 1, the circuit is closed and the sand 21 is 65 passing from the compartment 18 which is

uppermost to the compartment 18' below the same. The compartments 18, 18' are provided with slidable globes 22, 22' held within the casing T by screw-threaded rings T', T² which are of a length less than the length of the casing compartments 18, 18' and the inner end of which limits the outward movement of the slidable globes 22, 22' and when the timing element T is first moved into the position illustrated, the globe of the compartment which is lowermost at the time will rest upon the arm 15^a of the lever 15. When the timing element has been moved to the position shown, and as a load of sand 21 sufficient to balance the weight 17 enters the sliding globe 22', it will be depressed into the dotted line position shown at 22^a and in such position will depress the arm 15^a of the lever 15 raising the opposite arm 15' and opening the switch S.

The timing element T is mounted for movement in one direction only by the handle 3. As illustrated, the said element is mounted on a spindle 23 supported at one end on a bracket 23' and at the other end has a fast connection with a bearing cup 24 which is fast on a spindle 24' supported in the box 1 and to which the handle 3 is connected by a screw 3'. The casing T of the timing element has fixed thereto a ratchet wheel 25 having teeth 25'. A disc 26, having a stop 26' adapted to engage at each half rotation with pins 27, 27', is mounted on the spindle 24' and carries a spring-pressed pawl 28 normally interlocking with one of the teeth 25' on the pawl wheel 25, so that when the disc 26 is rotated a half turn by the handle 3, it will carry the box or casing T with it a half turn. The spring 29 will be wound up during such manual movement of the handle and will thereupon reversely rotate the handle and the disc 26 so that the pawl 28 will engage behind another tooth 25' on the disc 25 and thus be ready to cause the next half turning movement of the timing element or box T. The pawl mechanism hereinabove described will thus cause rotation of the timing element T in one direction only by the handle 3.

As above indicated, the circuit E will be made by the movement of the coin C into the position between the terminal portions 5 and 6 respectively and the coin will remain in position until released. This is accomplished by contact by the timing element in its next rotary movement, and, as shown, by contact of one of the globes 22, 22^a with a lever arm 12^b pivoted at 12^c and carrying the spring-pressed projecting contact 12' which holds the coin in position, it being understood that depression of the lever arm 12^b will raise the contact 12 and release the coin C which will then fall by gravity into a receptacle not shown. It will, therefore, be necessary to insert a new coin in order to procure additional operation of the motor or additional

electric current. Rotary movement of the timing element T will also release the weighted lever 15 and immediately cause a remaking of the circuit at the switch S. Immediately thereafter, however, the depression of the lever 12^b will cause the lifting of the contact 12, the release of the coin C and the breaking of the circuit at this point. Movement of the element T, therefore, will cause an automatic closing of the switch S and an opening of the circuit through the coin. In order to prevent a full movement of the box T before a coin is inserted, I preferably provide a weighted lever 31 pivoted at 31' and having attached at the pivoted point an arm 31^d provided with a weight 31^e, and also having its lower end 31^a projecting into the path of movement of the box. While the opposite end 31^b has its nose 31^c projecting through the slot t into the path of the coin so that a movement into the box of the coin will depress the end 31^a of the lever 31 out of the path of the box T and permit a turning thereof when a coin is inserted but until such a coin is inserted will block an inverting movement of the timing element T.

Assuming now that a coin is deposited and assumes the position C' shown at the top of Fig. 1, the nose 31^c of the lever 31 will, by the coin, be pressed outwardly and the end 31^a will thus be moved out of the path of movement of the box. The box may then be rotated and in its further rotary movement engage an arm 30^b of a lever 30 pivoted at 30^a on the coin-chute and normally held in operative position by a spiral spring 30^c stretched between a suitable pin 30^d on the coin-chute and an intermediate eye 30^e on the said lever. Withdrawing the end 30' of said lever out of the path of the coin will then cause it to fall into the position shown in full lines at the bottom of Fig. 1, to connect the circuit across the terminals 5 and 6. Further movement of the box will cause the globes 22 to be positioned over the end 15^a of the lever 15 and sand will immediately begin to pass through the drip opening 20 into that compartment. In order to maintain one of the casings T in proper operative position over the lever 15^a, I preferably provide the box with tracks 32, 32' fixed on the box and adapted to contact with a spring-pressed ball 33 mounted in a cage 34 and to guide the same into one of the sockets 35, 35' in said tracks.

In operation, therefore, the user, in order to obtain additional operation of the motor or additional current through the circuit E will pass a coin through the slot 2. This coin will move the nose 31^c outwardly and will be brought to rest in the dotted line position indicated at C' against the end 30' of a lever 30. Movement of the timing element T by the handle will release the coin from the dotted line position C' and cause it to drop into circuit-making position between the terminals and also cause the positioning of the

sand-dripping compartments to produce a breaking of the circuit across the switch at the end of a predetermined time period.

Having described my invention, I claim:—

In a coin-controlled timing device for electrically-actuated refrigerators and like machines, an electric switch, means for operating said switch embodying a sand-actuated timing element having a plurality of compartments communicating through a drip aperture and mounted for rotation to cause alternate dripping of the sand from one compartment into the other, means for operating said switch at the end of the movement of a predetermined quantity of sand through said aperture, a weighted lever normally operative to close said switch and operable by the weight of sand in one of said compartments to overbalance said weight and open the circuit, means for manually rotating said timing element in one direction and preventing rotation in the opposite direction, and coin-controlled means releasable by the movement of said timing element for closing said circuit at a different point.

In witness whereof, I have signed my name to the foregoing specification.

RICHARD SAUSE.
